UNITED STATES PATENT OFFICE.

JULIUS CHEIN, OF NEW YORK, N. Y.

DESIGN FOR A TOY FILLING STATION.

Application filed July 30, 1924. Serial No. 10,319. Term of patent 3½ years.

To all whom it may concern:

Be it known that I, JULIUS CHEIN, a citizen of the United States, residing at the Borough of Manhattan, in the city of New York, county of New York, and State of New York, have invented a new, original, and ornamental Design for a Toy Filling Station, of which the following is a specification, reference being had to the accompanying drawing, forming part thereof.

Figure 1 is a side view of a toy filling station, showing my new design, and

Figure 2 is a front view of the same.

I claim:

The ornamental design for a toy filling station, as shown.

In testimony whereof, I, JULIUS CHEIN, have signed my name to this specification this 24 day of June, 1924.

JULIUS CHEIN.
